[57] CLAIM

The ornamental design for a shoe sole foot frame, as
shown and described.

DESCRIPTION

FIG. 1 is a side elevational view of one shoe sole front
frame showing my new design;

FIG. 2 is a cross-sectional view taken along line 2—2 of
FIG. 1;

FIG. 3 is a side elevational view of the other shoe sole
foot frame shown in FIG. 1;

FIG. 4 is a rear elevational view of the shoe sole foot
frame showing in FIG. 1; and,

FIG. 5 is a cross-sectional view taken generally along
line 5—5 of FIG. 3.

The broken line showing of a shoe sole, including the
cupped vertical sides of the sole, and the broken line
showing of a shoe upper, are for illustrative purposes
and form no part of the claimed design.
